UNITED STATES PATENT OFFICE.

ALEXANDER ANDERSON, OF DETROIT, MICHIGAN, ASSIGNOR TO EARL HOLLEY, OF DETROIT, MICHIGAN.

MOLD CLEANING, HEATING, AND LAMPBLACKING DEVICE.

Application filed March 26, 1924. Serial No. 701,931.

To all whom it may concern:

Be it known that I, ALEXANDER ANDERSON, a citizen of the United States, residing at 9299 Cascade Avenue, Detroit, in the county 5 of Wayne and State of Michigan, have invented certain new and useful Improvements in Mold Cleaning, Heating, and Lampblacking Devices, of which the following is a specification.

10 This invention relates to an improved burner for the uniform distribution of lampblack upon a series of permanent molds mounted upon a rotating table, the said burners being adapted for heating, cooling 15 and cleaning the metal molds. This invention is a continuation of my co-pending application, Serial No. 661,378, filed September 7, 1923.

Figure 1 shows a cross sectional elevation 20 of the burner taken on the plane 1-1 of Figure 2.

Figure 2 shows the application of this burner to the mechanism described in my co-pending application, Serial No. 633,903, filed 25 April 23, 1923.

In Figure 1, A is the body of the burner. This burner is cored out and contains within it the passage B. This passage is provided at C with a threaded entrance which serves 30 as a supporting means for the burner and also as a conduit through which the combustible gas is admitted to the burner. The main casting A is also provided with a second entrance D through which the cooling, 35 cleaning and heating gases are admitted.

Outlets E are provided for the cooling, heating and cleaning gases and to these outlets E the nozzles F are connected which direct the cooling, heating and cleaning 40 gases against the surface of the molds. The cored passage B connects with the outlets G to which the nozzles H are threaded. These nozzles H direct the flame of the carbon depositing gas against the surface of the molds. A drain plug J is provided in the casting A for removing any moisture that 45 may be deposited therein from the compressed air.

A flexible pipe K connects with the entrance C to the casting A. A second flexible pipe L connects with the entrance D. Compressed air and illuminating gas are supplied through L and acetylene and air are alternately supplied through K, the air being admitted through the pipe R and con-

trolled by the valve T. A valve M controls the supply of illuminating gas. A valve N controls the supply of compressed air and the valve O to the pipe K controls the supply of acetylene.

The casting A is shown suspended by the mechanism described in my co-pending application referred to, which consists of an arm P which rotates about a center piece Q and rides on an inclined track Y, the track 60 Y being supported by the stationary arm S. A roller Z is provided to reduce the resistance to movement. The molds U V, which are shown in the open position, carry a projecting arm W which contacts with the arm P. The molds U V rotate about the same center as the piece Q and the arm P. The arm W therefore carries the arm P and the casting A with the molds U V.

The track Y, however, is inclined so that 70 as the molds rotate the arm P and the casting A are raised until the arm P clears the arm W, upon which the casting A and the arm P return to their initial positions running down the inclined track Y and re-engaging with the next succeeding molds. The molds U V are carried by the rotating table 75 X upon which the molds U V rotate and also move into and out of engagement with each other.

Operation.—Immediately prior to running the machine the valves O and M are closed, the valve N is opened and the molds are thoroughly cleaned by the compressed air issuing out of the nozzles E. The valve 80 N is almost closed and the valve M opened, and ordinary city gas ignited in the burners F. This gas flame is allowed to play on the molds U V until such time as they have 85 reached a sufficiently high temperature, 90 which is 500° or 600° F. The table X is then rotated and another pair of molds are heated until all the molds on the table have 95 been heated to the desired temperature. The valve M is then closed, the valve O is 100 opened and the acetylene flame allowed to play upon the molds U V, the gas issuing out of the nozzles H. The molds are thereafter coated with lampblack every time the table X carrying the molds U V rotates.

In the event that the acetylene nozzles H H are clogged with lampblack the valve 105 O is closed, the valve T is opened and the burners are thus cleaned. However, the compressed air supplied through T B and 110

burners H is inadequate for the cleaning of the molds and is merely for the purpose described.

The metal molds are preferably protected 5 with the coating described in the U. S. Patent #1,453,593, issued to Daniel H. Meloche on the 1st of May, 1923.

I prefer not to use the nozzle H for the compressed air and I prefer not to use the 10 nozzle F for the acetylene, for the reason that I have found it preferable to make the nozzle H $\frac{1}{16}$ " in diameter, whereas the nozzle F may well be $\frac{3}{16}$ " in diameter as a much greater rate of flow of compressed air or 15 heating gas is desirable than is the desirable flow of acetylene or other lampblack depositing gas.

What I claim is:

1. In a combined lampblack burner, 20 cleaner and heater, a passage for the admission of lampblackening depositing gas, a

separate chamber for the admission of heating and cleaning gases, burners for the heating and cleaning gases, separate burners for the lampblackening gas.

25

2. A device of the character described comprising a casing having a plurality of passages therethrough terminating in jet nozzles, means for alternately admitting lampblack depositing, heating and cleaning 30 gases through said passages to said nozzles.

3. In a combined lampblack burner, cleaner, and heater, a passage for the admission of lampblackening depositing gas, alternative means for admitting compressed air to said passage, a separate chamber for the admission of heating and cleaning gases, nozzles for the heating and cleaning gases, separate burners for the lampblackening gas.

In testimony whereof I affix my signature.

ALEXANDER ANDERSON.
